UNITED STATES PATENT OFFICE.

FORREST L. ELLISON, OF EXETER, NEW HAMPSHIRE, ASSIGNOR OF ONE-HALF TO
FRANK B. REDMAN, OF EXETER, NEW HAMPSHIRE.

MCKAY-SEWED WELT SHOE AND METHOD OF MAKING THE SAME.

Application filed June 24, 1927. Serial No. 201,089.

The object of this invention is to provide a McKay-sewed shoe in which advantageous features of an ordinary McKay shoe, a Goodyear welt shoe, and a turned shoe, as 5 ordinarily constructed, are combined, at an expense considerably less than that involved in making either a Goodyear welt or a turned shoe.

I attain this object by the improved construction and method hereinafter described and claimed.

Of the accompanying drawings forming a part of this specification,—

Figure 1 is a fragmentary perspective view, showing portions of the insole and welt of a shoe constructed in accordance with the invention.

Figure 2 is a fragmentary perspective view, showing the welted inside portion 20 shown by Figure 1, and portions of an upper and a last.

Figure 3 is a fragmentary perspective view, showing portions of a bottom filler and an outsole applied to the assemblage 25 shown by Figure 2, the last being omitted.

The same reference characters indicate the same parts in all of the figures.

In the drawings, 12 designates an insole, and 13 a welt laid on the outer side of the 30 insole with its outer margin substantially flush with the margin of the insole, the width of the welt being such that its inner edge portion is adapted to receive inner stitches 14, passing through the welt and the insole, its central portion is adapted to receive curved inseam stitches 15, and its outer edge portion is adapted to receive McKay stitches 16, the central and outer edge portions being located outside the inner 35 stitches which pass through the inner edge portion of the welt.

After the attachment of the welt, the insole is applied to a last 17, and temporarily secured thereto by tacks. An upper 18 is 40 then applied right side out, by the usual lasting operation, to the last and insole, the inturned margin of the upper being laid on the welt. The upper may be temporarily secured by tacks driven through the marginal portion, the welt, and the insole, into the last, as in the lasting operation employed in making Goodyear welt shoes. The marginal portion of the upper is then 45 united to the welt by the curved inseam stitches 15, formed by a curved needle

stitcher, said stitches being interlocked with the inner stitches.

The bottom is then pounded down and a bottom filler 19, of any suitable nature, is applied to the portion of the insole exposed 60 within the welt and the marginal portion of the upper, a shank stiffener being introduced at the shank portion, if desired.

An outsole 20 is then laid on the marginal portion of the upper and preferably cemented thereto, the outsole having the usual McKay stitch-receiving channel covered by a lip 21. The parts thus assembled are then removed from the last, and the outsole is secured by the McKay stitches 16, 70 laid in the channel, while the lip 21 is displaced, the stitches passing through the outsole, the marginal portion of the upper, the outer edge portion of the welt, and the insole, the lip 21 being then closed and the 75 bottom finished as usual in a McKay-sewed shoe.

The shoe thus constructed has the following advantages over an ordinary McKay shoe. There are no tacks in the completed shoe to 80 work into the foot-receiving space. The shoe may be inexpensively made, by using a leatherboard insole and a leather welt, the stitches 14, 15 and 16 being all engaged with the welt, which, when made of the 85 usual welt leather, provides a suitable anchorage for the stitches, although the insole is made of cheaper and less efficient anchoring material, such as leatherboard. In consequence of the fact that the welt is stitched 90 to the insole, the upper is stitched to the welt, and the outsole is stitched through the upper, the welt and the insole, there are two series of stitches, viz., the stitches 15 and 16, directly engaged with the upper and 95 preventing it from being ripped away.

It is feasible to provide the outsole with a feather edge, as in a turn shoe, and the shoe when provided with this form of edge, can be tapped, which cannot be said of a 100 turned shoe. I have found that a shoe thus constructed, excludes moisture better than an ordinary McKay shoe, and is free from liability to squeak.

The welt when made of leather, is preferably provided in the outer side of its central portion with a longitudinal groove 23, which permits the portions of the upper engaged by the inseam stitches 15 to sink into the welt, so that the portions of said stitches 110

formed on the surface of the upper, are correspondingly sunken, and do not form projections on the upper liable to form ridges on a relatively thin outsole laid thereon.

- 5 If desired, the welt may be made of a cheaper material than leather, such as canvas, in which case, the groove 23 may not be provided.

I claim:

- 10 1. A McKay-sewed welt shoe, comprising an insole, a welt laid on the outer side of the insole with its outer margin substantially flush with the margin of the insole, inner stitches uniting the welt to the insole and located nearer the inner than the outer margin of the welt, the width and location of the welt being such that its inner edge portion receives the inner stitches, and its central portion and outer edge portion are located outside the inner stitches, an upper having an inturned marginal portion laid on the welt, curved inseam stitches uniting the marginal portion of the upper to the central portion of the welt, and interlocked with the inner stitches, an outsole laid on the marginal portion of the upper, and McKay stitches passing through the outsole, the marginal portion of the upper, the outer edge portion of the welt, and the insole.
- 15 2. A McKay-sewed welt shoe as specified by claim 1, the welt having a groove in the outer side of its central portion, permitting the portions of the upper engaged by the in-

seam stitches to sink into the welt, so that the portions of said stitches formed on the upper, are correspondingly sunken and do not form projections on the marginal portion of the upper.

3. That improvement in the method of making a McKay-sewed welt shoe, which consists in applying a welt to an insole with its outer margin substantially flush with the margin of the insole, uniting the welt to the insole by inner stitches passing through the inner edge portion of the welt and the insole, the central and outer portions of the welt being outside the inner stitches, applying the insole to a last, applying the upper to the last and insole with the marginal portion of the upper inturned on the welt, uniting the marginal portion of the upper to the welt by curved inseam stitches passing through the central portion of the welt and interlocked with the inner stitches, removing the upper and insole from the last, applying a bottom filler to the exposed portion of the insole, laying an outsole on the filler and on the marginal portion of the upper, and securing the outsole by McKay stitches passing through the outsole, the marginal portion of the upper, the outer edge portion of the welt, and the insole.

In testimony whereof I have affixed my signature.

FORREST L. ELLISON.
